UNITED STATES PATENT OFFICE

EDWARD L. COMBS, OF CAMDEN, NEW JERSEY, ASSIGNOR TO THE POOLEY COMPANY,
OF PHILADELPHIA, PENNSYLVANIA, A CORPORATION OF PENNSYLVANIA

DESIGN FOR A RADIOCABINET

Application filed January 11, 1929. Serial No. 29,569. Term of patent 3½ years.

To all whom it may concern:

Be it known that I, EDWARD L. COMBS, a citizen of the United States, residing at 335 N. 38th Street, Camden, county of Camden, State of New Jersey, have invented a new, original, and ornamental Design for Radiocabinets, of which the following is a specification, reference being had to the accompanying drawings, forming a part thereof.

Fig. 1 is a perspective view of a radio cabi-

net in closed position embodying my design. Fig. 2 is a perspective view of a radio cabinet in open position embodying my design.

I claim:

The ornamental design for a radiocabinet, as shown.

In testimony of which invention, I have hereunto set my hand, at Philadelphia, on this 10th day of January, 1929.

EDWARD L. COMBS.
